UNITED STATES PATENT OFFICE.

ALBERT J. MORLOCK, OF NEW YORK, N. Y.

REDUCTION SYSTEM.

992,027.

Specification of Letters Patent.

Patented May 9, 1911.

Application filed June 27, 1910. Serial No. 569,032.

To all whom it may concern:

Be it known that I, ALBERT J. MORLOCK, a citizen of the United States, and a resident of the city of New York, borough of Brooklyn, in the county of Kings and State of New York, have invented a new and Improved Reduction System, of which the following is a full, clear, and exact description.

My invention relates to reduction systems used for cooking, reducing and converting garbage, offal, slaughter-house tankage, dead animals and fish, and materials of various kinds, for the double purpose of ridding communities of the various objectionable materials mentioned and of making various products and by-products by working up the same.

My present invention is associated more or less remotely with that described in my Patent No. 931,457, of August 17, 1909, for a separator, some of the parts in my present invention being similar to parts described in my said patent.

Among the objects which I seek to accomplish by my present invention are the following: I. To provide for saving greases and oils which may accumulate from time to time in the reduction tank under conditions where ordinarily these materials might be wasted. II. To prevent undue liberation of noxious gases and vapors to the detriment of health and comfort of people living in the vicinity. III. To so connect up a number of presses with pressure tanks that a single pressure tank may be used to fill two presses, thereby enabling the presses to be made smaller than would otherwise be necessary. IV. To improve the general efficiency of reduction systems by improving the construction and action of various parts used in connection therewith.

Reference is to be had to the accompanying drawings forming a part of this specification, in which similar characters of reference indicate corresponding parts in both the figures.

Figure 1 is a fragmentary elevation showing my improved reduction system; and Fig. 2 is a detail showing one of the presses and the pressure tank immediately connected therewith, this view further showing the by-pass for dividing the contents of either pressure tank so as to fill two presses of smaller size.

55 A framework 3 supports conveyer mecha-

nism 4, the latter including rollers 5, 6. At 7 is a platform associated with the conveyer mechanism, and at 8 is a swiveled chute supported by the platform 7 for the purpose of transferring materials from the latter. The parts just enumerated being old and well-known, need no further description. The framework 3 includes large supporting beams 9 disposed horizontally.

At 10, 11 are reduction tanks, the tanks being provided with lugs 12 which engage the horizontal beams 9.

At 13, 14 are pressure tanks and below these are the presses 15, 16, these presses being substantially of the kind described in my Patent No. 931,457, referred to above.

At 17 is a by-pass connecting the two pressure tanks 13, 14 directly together. This by-pass is controllable by a hand valve 17^a (see Fig. 2) and by aid of said valve may be opened and closed at the will of the operator. Steam pipes are shown at 18, 19 and are fed with live steam from a supply pipe 20. The pipes 18, 19 are provided with hand valves 21, 22, by aid whereof steam may be thrown into either pipe 18 or 19, or into both, as desired.

At 23, 24 are hand valves for opening and closing communication between the pressure tank 14 and the press 16. Steam pipes 25, 26 are connected respectively with the bottom of the reduction tank 11 and top of the pressure tank 14, and are controllable by hand valves 27, 28, the steam being supplied to the pipes 25, 26 through the supply pipe 29. Each press 16 is provided at its bottom with a swinging door 30, this door carrying an outlet pipe 31. The door also carries a fork 32 in which is a roller 33 running upon a circular track 34 and supporting the weight of the door 30 together with such pressure as may be exerted on said door. A steam pipe 35 is connected with the reduction tanks 11, 10 by pipes 36, 37. At 38 is a trap which is also connected with the pipe 35. A pipe 39 leads from the trap 38 to a condenser 40, the latter being controllable by a hand valve 41 and being provided with an outlet pipe 42. Connected with the bottom of the trap 38 is a discharge pipe 43 which extends downwardly and is provided with a hand valve 44 whereby it may be opened and closed.

At 45 are platforms and mounted upon

the same are railings 46 for the convenience of the operator.

At 47 is a conveyer belt which runs upon pulleys or rollers 48 and is used more particularly in connection with emptying the presses 15, 16.

At 49 is a pipe leading to a condenser 50, the latter being controllable by aid of a hand valve 51. Extending from the pipe 49 to the pressure tanks 13, 14 are pipes 52, 53. These pipes are provided with hand valves 54, 55.

At 56, 57 are hand valves controlling communication between the reduction tanks 10, 11, and the pressure tanks 13, 14.

The operation of my device is as follows: The material to be operated upon, and which may consist of garbage, offal, slaughter house tankage, and the like, is thrown into 20 the swivel chute 8 and allowed to glide obliquely downward into the reduction tank 11. For this purpose the hand valve 57 is previously closed. The reduction tank 10 may, if desired, be filled in the same manner. The tops of the reduction tanks being closed tight, steam is now admitted through the pipes 25 and the materials contained in the reduction tanks are thus heated and cooked. Suppose, now, that owing to splashing taking place in the reduction tanks 10, 11, caused by accidental irregularities in heating or lack of homogeneity in the material operated upon, it should happen that the portions of solid matter are driven upward through the pipes 36, 37. These portions of solid matter are driven along through the pipe 35 and into the trap 38. It happens that the greases and oils from the material nearly always float on top of the 40 materials, and thus being uppermost they are liable to be forced upward through the pipes 36, 37. If this happens, greases and oils are taken into the trap 38 along with the solid matter, and as this trap is partially 45 filled with water upon which the greases and oil float, the latter may be readily tapped off at any time by aid of the discharge pipe 43 and the hand valve 44. All steam, vapors and gases, including such 50 vapors and gases as are noxious or possibly poisonous, are free to pass upwardly from the trap 38 and through the pipe 39 to the condenser 40 where they are, as far as practicable, condensed and discharged in liquid form through the outlet pipe 42. In the trap 38 the lower end of the pipe 35 normally dips below the level of the liquid contained therein, though this is not by any means necessary. The materials being completely cooked and reduced in the reduction tanks 10, 11, are next transferred downwardly through the pressure tanks. This is done by opening the valves 56, 57. The pressure tanks being thus filled, 65 the valves 56, 57 are closed and steam is ad-

mitted through the pipe 18 by aid of the hand valves 21. If at any time an overflow takes place from the pressure tanks 13, 14, or if for any reason greases, solid matter or other portions of the materials operated upon are thrown upwardly through the pipes 52, 53, they pass into the pipe 49 and along with steam and various vapors and gases are carried to the condenser 50, being rendered, by action of the condenser, as harmless and as compact as possible. This enables these materials to be saved, in so far as they may be worth saving. If need be, live steam may be supplied to the pipe 18 and the materials cooked still further in the pressure tanks. The stirring of the materials, due to their transfer from the reduction tanks down into the pressure tanks, frequently places them in a condition to be cooked further by the application of fresh 85 steam. The process being practically finished, the next step is to run the converted materials from the pressure tanks 13, 14 into the presses 15, 16. To do this the valves 56, 57 are closed, and the valves 23, 24 of either of the presses are next opened. Steam being now admitted through the pipe 26, the materials are forced downward by steam pressure, so as to fill one of the presses. The by-pass 17 being opened by aid of the valve 17^a (see Fig. 2) a portion of the materials is forced through the pipes into the opposite pressure tank if this tank happens to be otherwise empty or happens to be spacious enough to receive the material.

Under ordinary circumstances, if the apparatus be used in connection with full charges of the material, each charge when thoroughly cooked and reduced is just about sufficient to fill the two presses. The pressure tanks 13, 14 are emptied alternately and if there be a large number of these tanks they are arranged in pairs, the two tanks of each pair being alternated in their action of discharging into the two presses. Any number of the pressure tanks 13, 14 may be used simultaneously up to the moment of discharging their contents into the press, but in discharging their contents the pressure tanks are operated one at a time.

In some instances I prefer to fill the materials into only one of the reduction tanks 10, 11 and when the reduction is complete, to transfer these materials straight downward into the pressure tank below and corresponding to the reduction tank thus used.

The difference in size of a reduction tank and its corresponding pressure tank represents the approximate shrinkage of the material, due to its cooking and to various losses which always take place during this operation. Where only one of the cooking tanks 13 is full or approximately full of the reduced material, there is economy in using both of the presses 15, 16, and this is done 130

by aid of the by-pass 17, as above described. That is to say, by using one pressure tank 13 or 14 and filling the two presses 15, 16, the work is done as rapidly as would be the case if the pressure tank in question were used with a single press of larger capacity. It is obvious that if a single pressure tank (13 or 14) can thus be used with both of the presses 15 and 16, and these presses can 10 consequently be made smaller than would otherwise be necessary—to wit, just half the capacity—the system as a whole is cheapened by the difference in the cost of large and small presses, and as these presses are 15 usually quite expensive, the saving is considerable. Moreover, it frequently happens that in plants of this kind there is a scarcity of room and especially of room extending vertically upward. By having the presses 20 15, 16 comparatively small, as above described, the available space is conserved in every sense, and even the building in which the plant is located may, if desired, be rendered slightly lower—other things being 25 equal—owing to the reduction in size of the presses. The materials being forced downwardly into the presses, the action inside of the presses, and subsequently to their filling, is substantially the same as that described in my patent above mentioned. The materials and products extracted therefrom are removed from the presses in the manner 30 already known in this art and described in my existing patent.

35 While I show the various reduction and pressure tanks as cylindrical, it will be understood that I do not limit myself thereby,

as these parts may be made in any convenient form.

My invention is useful in connection with 40 the destruction and working up of the materials mentioned, around large cities where they accumulate and must necessarily be disposed of in some suitable manner. By aid of the system above described the materials 45 may be disposed of at considerable advantage, the various products and by-products being oftentimes of considerable value.

Having thus described my invention, I claim as new and desire to secure by Letters Patent:

1. The combination of a plurality of pressure tanks, a by-pass connecting the same together, a separate press connected with each of said pressure tanks, and means for 55 applying pressure to materials contained within one of said pressure tanks for the purpose of causing a portion of said materials to pass across from one pressure tank to another in order to fill all of the presses. 60.

2. In a reduction system, the combination of a plurality of pressure tanks, a plurality of presses each connected with one of said pressure tanks, valves disposed between said pressure tanks, and a by-pass extending 65 from one of said pressure tanks to another.

In testimony whereof I have signed my name to this specification in the presence of two subscribing witnesses.

ALBERT J. MORLOCK
